UNITED STATES PATENT OFFICE.

DANIEL JAMES McOMISH, OF NORTHCOTE, VICTORIA, AUSTRALIA.

INFANT'S SOOTHING TEAT.

Application filed September 14, 1921. Serial No. 500,481.

To all whom it may concern:

Be it known that I, DANIEL JAMES McOMISH, a subject of the King of Great Britain and Ireland, and a resident of the city of 5 Northcote, a suburb of the city of Melbourne, in the county of Bourke, State of Victoria, Commonwealth of Australia, whose post office address is 8 Smith Street, Thornbury, in the said city of Northcote, 10 have invented certain new and useful improvements in and connected with Improvements in Infants' Soothing Teats, of which the following is a specification.

This invention relates to infants' soothing 15 teats of the kind comprising an elastic bulb or nipple, a screw threaded connecting pin which fits into one end of the teat, a cap or mount which screws onto said pin and the usual shield which is positioned between the 20 mount and the nipple. In soothing teats of the above type as at present constructed the parts are liable to become disconnected thus incurring danger of the shield being detached and the nipple and other parts thus 25 swallowed by the infant. Furthermore, the bulb or nipple is completely sealed by the connecting pin thus forming an air tight or pneumatic chamber within the bulb. This renders the teat objectionable owing to its 30 comparative hardness and liability to derangement in the event of a faulty joint between the bulb and connecting pin and consequent collapse of the teat owing to outward leakage of air when the bulb is compressed 35 and no corresponding air admission when the pressure is relaxed.

The primary object of the present invention is to provide in a soother of the above 40 type, means whereby it is practically impossible for the shield to become accidentally detached from the nipple, and whereby the interior of the elastic teat or bulb is in permanent and free communication with the atmosphere through air passages formed in 45 the threaded connecting pin and in the cap or mount which screws on to said pin. By this means the article is rendered safer and more efficient and attractive to the infant, and less liable to derangement. The invention 50 also enables the various parts to be readily disconnected and re-assembled when desired for cleansing or other purposes thus rendering it perfectly hygienic.

Referring to the drawings which form part of this specification:—

Figure 1 is a side elevation of a rubber bulb or nipple in accordance with the invention.

Figure 2 is a longitudinal section of the improved form of connecting pin used in accordance with the invention and showing the air passage therethrough.

Figure 3 is a diametrical section of the shield.

Figure 4 is a longitudinal section of the cap or mount which screws on to the pin seen in Figure 2.

Figure 5 is an end view of Figure 4.

Figure 6 is a side view showing the connecting pin inserted in the open end of the 70 rubber bulb.

Figure 7 is a longitudinal section showing the parts assembled to form the complete article.

As seen in the drawings the numeral 2 75 indicates the rubber bulb or nipple which constitutes the teat proper and is preferably formed as in Figure 1 with an enlarged or swollen neck 3 and an external head 4 around its inner or open end.

In combination with said bulb a connecting pin as seen in Figure 2 is employed. This pin is preferably constructed of bone, ivory or like material and is provided at one end with an externally threaded stem 6 85 and at its other end with an enlarged circular head 7. Between the threaded portion 6 and the head 7 is an intermediate plain circular portion or neck 8 of slightly larger diameter than said threaded portion.

In accordance with the invention a longitudinal air passage 9 is formed through the connecting pin from end to end thereof and this passage communicates with the interior of the bulb 2 when the parts are assembled 95 as in Figure 7, the head 7 forming a tight fit in the neck 3 whilst the beaded end 4 of the bulb encircles the neck 8 of the connecting pin as shown.

The usual shield 11 fits around the end of 100 the bulb between the bead 4 and head 7 and surrounding the neck 8 as in Figure 7. The shield is thus securely held in position and if desired the central hole through the shield may be grooved or serrated to increase the 105 grip on the rubber nipple.

The cap or mount 12, is also preferably made of bone, ivory or the like and is provided with a threaded central hole 13 which receives the threaded portion 6 of the connecting pin. In accordance with the invention this hole 13 also constitutes an air passage which communicates with one or more radial air passages 14 extending to the surface of the cap. The radial air passages 10 may also serve to accommodate the usual cord for attaching the article to the infant.

It will be seen from the foregoing that when the parts are assembled as in Figure 7 they are retained securely together by the connecting pin the shield 11 being so held that even in the event of the cap 12 becoming unscrewed it is practically impossible for the shield to be accidentally displaced. Thus the danger of the nipple or other parts 20 passing down the infant's throat is eliminated. At the same time the interior of the bulb 2 is in permanent communication with the atmosphere by way of the passages 9, 13 and 14. The teat will thus always return to its normal shape after compression and the article is rendered more flexible and soothing to the infant than the air tight or pneumatic teats of somewhat similar construction at present in use.

30 To dismantle the parts for cleansing it is

merely necessary to unscrew the cap 12 whereon the shield may be drawn forcibly over the bead 4 and the connecting pin may be withdrawn from the rubber nipple.

Having now described my invention what I claim as new and desire to secure by Letters Patent is:—

An infant's soothing teat, comprising a nipple having an open end, an enlarged neck adjacent said end and an external bead at 40 said end, a connecting pin having an enlarged head adapted to fit tightly within said neck, a cylindrical portion extending from said head and terminating beyond the beaded end of the nipple and a reduced 45 threaded end extending from the cylindrical portion, a shield formed with a central opening fitting over the pin and the end of the nipple between the bead and the enlarged neck of the nipple, and confining the nipple 50 adjacent the bead to the cylindrical portion of the pin, whereby the nipple is positively retained on the pin by the shield, and a cap adapted for threaded engagement with the 55 threaded end of the pin.

In testimony whereof I affix my signature.

DANIEL JAMES McOMISH.

Witness:

CARL W. P. CLASHETT.
